US0D1081600S

(12) **United States Design Patent** (10) **Patent No.:** **US D1,081,600 S**
(45) **Date of Patent:** **** Jul. 1, 2025**

(54) **CONTROLLER FOR HOME AUTOMATION**

(71) Applicant: **Weijian Qiu**, Shenzhen (CN)

(72) Inventors: **Junxian Qiu**, Shenzhen (CN); **Weijian Qiu**, Shenzhen (CN)

(73) Assignee: **Weijian Qiu**, Shenzhen (CN)

(**) Term: **15 Years**

(21) Appl. No.: **29/907,548**

(22) Filed: **Jan. 8, 2024**

(30) **Foreign Application Priority Data**

Nov. 3, 2023 (CN) 202330718770.X

(57) **CLAIM**

The ornamental design for a controller for home automation, as shown and described.

DESCRIPTION

FIG. 1 is a front, left and bottom perspective view of a controller for home automation, showing our new design; FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
